F. J. BACKSCHEIDER.
ELECTRICAL SWITCH.
APPLICATION FILED JUNE 30, 1913.

1,248,787.

Patented Dec. 4, 1917.

UNITED STATES PATENT OFFICE.

FRANK J. BACKSCHEIDER, OF CINCINNATI, OHIO.

ELECTRICAL SWITCH.

1,248,787.

Specification of Letters Patent.

Patented Dec. 4, 1917.

Application filed June 30, 1913. Serial No. 776,518.

To all whom it may concern:

Be it known that I, FRANK J. BACKSCHEIDER, a citizen of the United States, residing in Cincinnati, in the county of Hamilton and State of Ohio, have invented a certain new and useful Improvement in Electrical Switches, of which the following is a full, clear, and exact description, reference being had to the accompanying drawings, forming part of this specification.

My invention relates to electrical switches for the instantaneous making or breaking of the electrical circuit, and particularly to such a switch in which the circuit may be automatically and instantaneously broken under predetermined conditions.

The object of my invention is to provide such a switch of efficient and durable construction, and one which is especially adapted to use in connection with my new clutch as described in application for Letters Patent of the United States, Serial Number 718,100 filed by me on August 31, 1912.

In the drawings:

Figure 1 is a section through the casing of my new switch, most parts of the switch itself being shown in elevation;

Fig. 2 is a section on line *a—a* of Fig. 1; Fig. 3 is a plan of the contacts;

Fig. 4 is a detail of the rocking frame and movable contacts;

Fig. 5 is a detail of the tension spring for automatic disconnection;

Fig. 6 is another detail of said spring.

The numeral 1 indicates a portion of the casing of a portable tool in connection with the use of which I have illustrated my new switch in the drawings. Mounted in said casing is the armature 2 having a shaft 3. Power from said shaft is transmitted through the clutch members 4 and 5. The driving, or positive member, 4, of said clutch is keyed onto the armature shaft, and, therefore, rotates therewith and is slideable thereon. The driven, or negative member, 5, is on the spindle 6. A coil spring 7 normally holds the clutch members in contact. The engaging faces of the members are, however, of such form that, when the spindle is over-loaded, the clutch members will separate by the recession of member 4 against the tension of spring 7.

On the casing 1 the box 8 is mounted, within which my new switch is housed. In the end of said box the handle 9 of the port-

able tool is secured. In the switch box 8 is a frame 10. Said frame is provided with a threaded socket 11 which extends through an opening in the box, and is adjustably secured in position in the box by means of a threaded bolt 12 mounted in standards 13 on the casing 1. Between the standards the bolt is thicker so that longitudinal movement thereof is prevented, and it will thus be seen that the turning of the bolt will provide adjustment for the frame 10 for the purpose hereinafter set forth. Mounted in the lower end of said frame is a shaft 14, said shaft being rigid in the frame. Rotatably mounted on said shaft is the rocking frame 15, which is composed of two side plates, shaped as clearly shown in Fig. 4, the upper edges being generally straight, but provided with middle notches, and the sides converging downwardly from the upper edges, the acute angles being, however, slightly rounded off. The sides of said rocking frame are joined at the bottom as shown in Fig. 1. Inserted in perforations in the side plates of the frame 15, near the bottom thereof, is a sleeve 16; said sleeve has a collar 17 which abuts against one of the plates and assists in maintaining rigidity in the attachment of the sleeve in the rocking frame, and prevents the insertion of the sleeve farther than will bring the end thereof even with the outer edge of the opposite side plate. Inside the sleeve 16 is a plunger 18 which is provided with a socket 19 for the ball bearing 20. Interposed between the socket shoulder and the end of sleeve 16 is a coil spring 21, which causes the ball 20 to rest normally near the flange 22 of the member 4 of the clutch, for the purpose hereinafter set forth. Pivotedly mounted on the shaft 14 is the operating lever 23, the shaft 14 projecting beyond the side of frame 10 for such purpose. The upper end of said lever extends through an opening in the switch box 8 and is therefore accessible for manual operation. Secured to the lower end of the operating lever is a sleeve 24, the free end of said sleeve extending to the side plate of frame 15, the opening in sleeves 16 and 24 being adapted to register when the sleeves are in alignment. In the sleeve 24 is a pin 25 provided with a head which abuts against a shoulder in the sleeve. The other end of said pin is rounded and abuts, when the head of the pin rests against the shoul-

der, against the end of the plunger 18, the pin 25 by extending into the end of sleeve 16 thus operatively connecting the operating lever 23 with the rocking frame 15. Between the head of the pin 25 and a plug 26 is a coiled spring 27, which normally holds the pin in the position above described. The plug 26 is threaded so that the tension of spring 27 may be adjusted.

10. Rotatably mounted on a floating shaft 28 are rollers 29, said rollers being adapted to ride on the upper edges of the side plates of the rocking frame 15; the floating shaft being anchored to the shaft 14 by means of 15 a coil spring 30. Also mounted on said floating shaft, are contact rollers 31 and 32, each of which is composed of a peripheral metal portion 33 and an intervening layer of insulating material 34 between the same and 20 the hub; contacts are therefore made independently through each roller. Secured to the frame 10 are fixed contacts 35, 36, 37 and 38, these are arranged in pairs, the contact plates being separated by non-conductive material 39. As shown in Fig. 1 the contact plates extend above the intervening material 39, and thereby form, with the intervening material, a grooved track for each of the rollers 31 and 32, the metal flanges 25 of the rollers being adapted to enter between the contact plates and to contact therewith in the manner illustrated. The contact plates are connected by wiring as shown in Fig. 3 so that by making contacts by means 30 of rollers 31 and 32 with plates 35 and 36 the motor will be driven in one direction, and by making such contacts with plates 37 and 38 it will be reversed.

Rotatably mounted in the frame 10 is a 40 shaft 40 to which is secured an operating arm 41; a pair of depending arms 42 and 43 is also rigidly secured to said shaft, the arm 42 being adapted, upon the proper rocking of the shaft 40 to rest against one side 45 of the floating shaft 28, and the arm 43 to rest against the same upon rocking the shaft 40 in the opposite direction. On each of the arms 42 and 43 is a stop 44 adapted to rest against the upper edge of the rocking 50 frame 15 when the frame is in neutral, or "off" position, as shown in full lines in Fig. 2, and the arm bearing the operative stop is resting against the floating shaft. The operating arm 41 extends through a slot 55 in the switch box so that it may be manually operated and the arms 42 and 43 appropriately rocked. Studs 45 are provided on the frame 10; one of these studs engages a perforation in the arm 41 when it reaches the 60 limit of its movement in either direction and locks the same. Similar studs, or catches 46 are provided on the switch box to lock the operating lever 23.

Wound around a thickened portion of the 65 shaft 14 is a heavy coil spring 47. Fixedly

secured to said shaft is a frame 48, the horizontal bar 49 of which passes between the ends of the spring 47; said ends also extend downwardly on opposite sides of the sleeve 16.

The operation of my switch is as follows: Assume, first, that the motor is to be driven in the forward direction; this having been determined, the arm 41 is thrown in the required direction, for instance to the position in which it is shown in Fig. 2, where it will be locked by the stud 45. The arm 43 will then rest against the floating shaft preventing its movement in the direction of its abutment so that the contacts can be moved only to one set of fixed contacts; the stop 44 on arm 43 will also rest against the upper side of the rocking frame and allow it to rock only in one direction, that is, to the position shown in broken lines in Fig. 2. It will thus be seen that the movement of the operating lever is now limited to movement in the direction required to make the necessary contacts for the forward drive of the motor. The arm 41 having been thus set, the operating lever is thrown in the required direction to the position shown by broken lines in Fig. 2. During such movement of the lever the rocking frame 15 is rocked, by reason of the engagement of pin 25 with sleeve 16, to the position also shown by broken lines in Fig. 2. While thus rocking the rollers 29 ride upon the upper edges of the side plates, movement in the direction of the movement of the rocking frame being prevented by the arm 43, and the floating shaft is forced away from the shaft 14 increasing the tension of spring 30. When the movement of the frame 15 brings the corners of the plates past the bearing of the rollers 29 on the frame, the spring 30 will instantaneously draw the floating shaft downward, the rollers 29 riding on the inclined side edges of the plates, and the contact rollers 32 and 33 will be thrown into the fixed contacts. When the circuit is thus completed the operating lever is locked in the "open" position by the stud 46 as above explained. In breaking the circuit the lever is thrown back, the contact rollers, by reason of the rollers 29 riding upon the moving side edges of the plates of frame 15, recede in a horizontal direction, the contacts being continuously maintained during such recession by reason of the length of the fixed contacts, until the corners of the frame 15 pass the rollers 29; then the spring will snap the floating shaft back to its bearing against the arm 43, when the contact will be broken and the rollers 20 will rest in the notches in the upper edges of the side plates. To reverse the motor, the arm 41 is thrown in the opposite direction, after which the operating lever is also thrown in the same direction, the operation being otherwise the same.

as above described, except that the roller contacts are thrown into the opposite fixed contacts.

When the circuit in either direction has been made by my new switch by the manual operation of the lever 23 as above set forth, such circuit will be automatically and instantaneously broken under predetermined conditions in the following manner. During the rocking of the frame 15 the spring 47 is wound up, so to speak, by the sleeve 16 which carries one end of the spring around with it, the other end thereof being held stationary by the bar 49. Thus there is a tension against the sleeve tending to force it, and the frame 15 back to the "off" position. When the spindle 6 is overloaded the member 4 of the clutch will recede against spring 7, as above set forth, and the flange 22 will in such movement strike the bearing 20 thus forcing back the plunger 18, which in turn will push back the pin 25 against the tension of spring 27. As soon as the rounded end of pin 25 is pushed slightly out of end of sleeve 16, the spring 47 will throw the rocking frame to the "off" position, the pin being forced all the way out of sleeve 16 by reason of the pin's rounded end, which acts as a cam when the curve is reached. When the rocking frame is thus thrown automatically to the "off" position, the contacts are, of course, instantaneously broken in the manner above set forth. It will be seen that this automatic action is the same whether the motor is driven forward or on the reverse, as both ends of the spring 47 are adapted to act on the sleeve 16 and throw the rocking frame 15. By means of bolt 12 the contact of flange 22 with the bearing 20 may be properly timed, as will be readily seen.

Having thus described my invention, what I claim as new and desire to secure by Letters Patent, is:

1. An electrical switch comprising fixed contacts, a floating member, movable contacts on said floating member and adapted to engage said fixed contacts, a tension member, said floating member being secured to said tension member, a rocking frame, said frame being adapted to serve as a support for said floating member when the switch is in off position, and to move the same against the tension of said tension member when rocked and to release the same when under tension, whereby said movable contacts are caused to engage said fixed contacts.

2. An electrical switch comprising fixed contacts, said contacts being wired for forward and reverse circuits, a floating member, movable contacts on said floating member and adapted to engage the forward or reverse fixed contacts, a tension member, said floating member being secured to said

tension member, a rocking frame, said frame being adapted to serve as a support for said floating member when the switch is in off position, and to move the same against the tension of said tension member when rocked in either direction and to release the same when under tension, whereby said movable contacts are caused to engage either the forward or reverse fixed contacts.

3. An electrical switch comprising fixed contacts, said contacts being wired for forward and reverse circuits, a floating member, movable contacts on said floating member and adapted to engage the forward or reverse fixed contacts, a tension member, said floating member being secured to said tension member, a rocking frame, said frame being adapted to serve as a support for said floating member when the switch is in off position, and to move the same against the tension of said tension member when rocked in either direction, and to release the same when under tension, whereby said movable contacts are caused to engage either the forward or reverse fixed contacts, and means to block the movement of said floating member toward either said forward or reverse fixed contacts to prevent contact therewith.

4. An electrical switch comprising fixed contacts, a floating member, movable contacts on said floating member and adapted to engage said fixed contacts, a tension member, said floating member being secured to said tension member, a rocking frame, said frame being adapted to serve as a support for said floating member when the switch is in off position, and to move the same against the tension of said tension member when rocked and to release the same when under tension, whereby said movable contacts are caused to engage said fixed contacts, means whereby said rocking frame is placed under tension during such engagement, means to lock said frame in position during such engagement, and means to release said frame whereby said movable contacts may be automatically thrown out of engagement with said fixed contacts by the return of said frame.

5. An electrical switch comprising fixed contacts, said contacts being wired for forward and reverse circuits, a floating member, movable contacts on said floating member and adapted to engage the forward or reverse fixed contacts, a tension member, said floating member being secured to said tension member, a rocking frame, said frame being adapted to serve as a support for said floating member when the switch is in off position, and to move the same against the tension of said tension member when rocked in either direction and to release the same when under tension, whereby said movable contacts are caused to engage either the forward or reverse fixed contacts, means where-

by said rocking frame is placed under tension during such engagement, means to lock said frame in position during such engagement and means to release said frame, whereby said movable contacts may be automatically thrown out of engagement with said forward or reverse fixed contacts by the return of said frame.

6. An electrical switch comprising fixed contacts, said contacts being wired for forward and reverse circuits, a floating member, movable contacts on said floating member and adapted to engage the forward or reverse fixed contacts, a tension member, 10 said floating member being secured to said tension member, a rocking frame, said frame being adapted to serve as a support for said floating member when the switch is in off position, and to move the same against the tension of said tension member when rocked in either direction and to release the same when under tension, whereby said movable contacts are caused to engage either the forward or reverse fixed contacts, means whereby 15 said rocking frame is placed under tension during such engagement, means to lock said frame in position during such engagement, means to release said frame, whereby said movable contacts may be automatically 20 thrown out of engagement with said forward or reverse fixed contacts by the return of said frame, and means to block the movement of said movable contacts toward either said forward or reverse fixed contacts to prevent contact therewith.
7. An electrical switch comprising fixed contacts, a floating member, movable contacts on said floating member and adapted to engage said fixed contacts, a tension member, said floating member being secured to 25 said tension member, a rocking frame, said 30 member, said floating member being secured to said tension member, a rocking frame, said 35 member, said floating member being secured to said tension member, a rocking frame, said 40 member, said floating member being secured to said tension member, a rocking frame, said

frame being adapted to serve as a support for said floating member when the switch is in off position, and to move the same against the tension of said tension member when 45 rocked and to release the same when under tension, whereby said movable contacts are caused to engage said fixed contacts, means whereby said rocking frame is placed under tension during such engagement, means to 50 lock said frame in position during such engagement, and means automatically to release said rocking frame whereby said movable contacts may be thrown out of engagement with said fixed contacts. 55

8. An electrical switch comprising fixed contacts, a floating member, movable contacts on said floating member and adapted to engage said fixed contacts, a tension member, said floating member being secured to 60 said tension member, a rocking frame, said frame being adapted to serve as a support for said floating member when the switch is in off position, and to move the same against the tension of said tension member when 65 rocked and to release the same when under tension, whereby said movable contacts are caused to engage said fixed contacts, means whereby said rocking frame is placed under tension during such engagement, means to 70 lock said frame in position during such engagement, means automatically to release said rocking frame whereby said movable contacts may be thrown out of engagement with said fixed contacts, and means for the 75 adjustment of said automatic release.

In witness whereof I have hereunto set my hand this 20 day of June, 1913.

FRANK J. BACKSCHEIDER.
